HINGE HOOK

Steven Havark, 5415 W. Barry Ave.,
Chicago, Ill. 60641

Filed June 20, 1974, Ser. No. 481,162

Term of patent 14 years

Int. Cl. D8—08

U.S. Cl. D8—260

FIG. 4

FIG. 3

FIG. 1

FIG. 2

FIG. 5

FIG. 1 is a side elevation of a hinge hook of the present invention;

FIG. 2 is a right side elevation of the hinge hook shown in FIG. 1;

FIG. 3 is a left side elevation of the hinge hook shown in FIG. 1;

FIG. 4 is a top plan view of the hinge hook shown in FIG. 1; and,

FIG. 5 is a bottom plan view of the hinge hook shown in FIG. 1.

I claim:

The ornamental design for a hinge hook, substantially as shown and described.
